Primary Examiner — Cathron Brooks*Assistant Examiner* — Sharon S Oum(74) *Attorney, Agent, or Firm* — Banner & Witcoff, Ltd.(57) **CLAIM**

The ornamental design for a display screen with graphical user interface, as shown and described.

DESCRIPTION

The FIGURE is a front view of a display screen with graphical user interface showing my new design.

The outermost broken line illustrates a display screen and forms no part of the claimed design. The other broken lines illustrate portions of the graphical user interface that form no part of the claimed design.
